(57) **CLAIM**

The ornamental design for a snack and drink holder, as shown and described.

DESCRIPTION

FIG. 1 is a top, right, front, three-dimensional perspective view of a snack and drink holder showing our new design; FIG. 2 is a top plan view of the snack and drink holder of FIG. 1;

FIG. 3 is a bottom plan view thereof;

FIG. 4 is a front elevational view thereof;

FIG. 5 is a rear elevational view thereof;

FIG. 6 is a left side elevational view thereof;

FIG. 7 is a right side elevational view thereof; and,

FIG. 8 is a top, right, rear three-dimensional perspective view thereof shown in a used condition.

In the drawings, the broken lines in FIGS. 1, 2, 3, 6 and 8 depict portions of the design that form no part of the claim.

1 Claim, 6 Drawing Sheets
